UNITED STATES PATENT OFFICE.

WILLIAM W. ROBERTSON, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

SPOOL FOR AXMINSTER LOOMS.

Application filed April 23, 1926. Serial No. 105,280.

This invention relates to spools for Axminster looms and it is the principal object of the invention to provide a steel head for the spools having a plurality of ears which are driven into the end of the wooden barrel of the spool and held against turning by a tongue pressed from the head and having contact with a metallic ferrule secured to the spool barrel in such a way as to prevent angular movement of the head with respect to the barrel.

It is a further object of the invention to form the ferrule as a collar which may be used to compress the end of the spool barrel so that the wooden portions thereof may more tightly grip the ears stamped from the steel head.

With these and other objects in view which will appear as the description proceeds, my invention resides in the combination and arrangement of parts hereinafter described and set forth in the claims.

In the accompanying drawings wherein I have shown a convenient embodiment of my invention,

Fig. 1 is a front elevation of a tube frame having the preferred form of my improved spool applied thereto,

Fig. 2 is an enlarged end elevation taken in the direction of arrow 2, Fig. 1,

Fig. 3 is a vertical longitudinal section on line 3—3 of Fig. 2,

Fig. 4 is a perspective view of the ferrule forming part of my invention,

Fig. 5 is a view similar to a portion of Fig. 3 but showing a modified form of the invention,

Fig. 6 is a vertical section on line 6—6 of Fig. 5, and

Fig. 7 is a detail perspective view of the tongue-receiving guard used in the modified form of the invention.

Referring to the drawings, particularly Figs. 1 to 4, there is shown a tube frame 10 having spool bearing brackets 11 on each end thereof, said bearings supporting the outer ends of spools S carried by the tube frame. A center bearing 12 is mounted on the frame intermediate the ends thereof to support the inner ends of the spools.

The outer end of each spool has a head 14 formed of pressed steel and having a web 15 which defines the outer limit of the yarn

space, while the inner end of each spool has a steel head 16 defining the inner limit of the yarn space. Each head 14 is held in place by a stud 17 passing through the head and having a shoulder 18 to engage the outer surface of the head, said stud entering the barrel 19 of the spool and being held therein by pin 20. Stud 17 is reduced and threaded as at 21 and passes through a wooden plug 22 passing transversely through the spool barrel. A gudgeon 23 on the outer end of stud 17 is received by bearing 11. Prongs 24 are struck from the web 15 and are driven into the wooden barrel 19 and said web also has struck therefrom a tongue 25 which leaves an opening 26 in said web.

Heads 16 are also provided with prongs 27 driven into the barrel and each head has a tongue 28 extending inwardly therefrom and forming an opening 29 in the head 16. The barrel has a slot 30 which is in alignment with the openings 26 and 29 and receives the tongues 25 and 28. Heads 16 are held in place by studs 31 which have complementarily formed enlarged ends 32 having interengaging driving contact with each other. The matter thus far described is of common construction and forms no part of my invention, being similar to the construction set forth in Patent No. 1,067,656.

When the spools such as set forth herein are put in the so-called setting frames to have the variously colored tuft forming yarns wound thereon, the heads of each spool engage rotating clutches and rotary movement is transmitted by the clutch to the barrel through the head. It has been found that the prongs 24 and 26 are not sufficiently long to hold the heads tightly, with the result that in time said heads become loose with regard to the spool barrel 19. I aim to overcome this objection by providing a portion of the groove 20 with metallic walls to contact with the tongues 25 and 28 and in carrying out the preferred form of my invention I provide a ferrule 40 for each end of each spool substantially as shown in Fig. 4, with a cylindrical body 41 and a recessed guard portion 42. Prior to assembly of the heads on the spools the ferrules are driven on the end of the barrels with the grooved portions 42 in alignment with the grooves 19.

The studs and heads are then applied, the tongues entering the grooved portions 42 of the collar and the prongs being driven into the wood, splitting or expansion of the latter being resisted by the cylindrical portion of the ferrules. Inasmuch as the grooved portions 42 receive the tongues and are in alignment with the groove 19, a rod R may be passed freely through the openings and into the grooves to clamp the warp threads (not shown) in the usual way.

In the modified form of my invention shown in Figs. 5, 6 and 7 I omit the ferrule construction and provide a guard 50 having side walls 51 and a bottom 52 which when assembled will occupy the same position with regard to the head and the spool as the slotted portion 42 of the ferrule 40.

In both forms of the invention sliding movement of the metal ferrule or guard away from the head is prevented by shoulder 53 formed in the barrel near the ends thereof, and the tongues are in contact with metal walls which fit the tongues snugly to prevent angular movement of the heads.

From the foregoing it will be seen that I have provided the slots in Axminster spools with short metallic walls which cooperate with the tongues of the heads, said walls serving not only to guide the tongue but also to prevent angular movement of the head with respect to the barrel of the spool. It is for this reason that the prongs will not become loosened and will retain their original holding contact with the wood of the spool. It will further be noted that in the preferred form of the invention the holding contact of the prongs with the wood is further enhanced by the cylindrical portion of the ferrule.

Having thus described my invention it will be apparent that changes and modifications may be made therein by those skilled in the art without departing from the spirit and scope of the invention, and I do not wish

to be limited to the details herein disclosed but what I claim is:

1. In a spool for Axminster looms, a wooden barrel having a longitudinal groove therein, a sheet metal head, prongs struck up from the head and driven into the wooden barrel, a tongue also struck from the head and extending into the slot of the barrel, and means providing metallic walls for the slot in the barrel adjacent the tongue, said tongue engaging the metallic walls and said means being held tightly to the barrel.

2. In a spool for Axminster looms, a wooden barrel having a longitudinal groove therein, a sheet metal head, prongs struck up from the head and driven into the wooden barrel, a tongue also struck from the head and extending into the slot of the barrel, means providing metallic walls for the slot in the barrel adjacent the tongue, said tongue engaging the metallic walls and said means being held tightly to the barrel, and a stud passing through the head and held in the barrel out of alignment with the tongue to hold the head to the barrel.

3. In a spool for Axminster looms, a wooden barrel having a longitudinal groove therein, a metallic ferrule surrounding the end of the wooden barrel and confining the end portions thereof, said ferrule being formed with a depression in its circumference which is in alignment with the groove of the barrel, a sheet metal head held to the barrel, prongs struck up from the head and driven into the wooden barrel to expand the wood against the ferrule, and a tongue also struck from the head and extending into that portion of the ferrule which is in alignment with the groove of the barrel, the tongue being thereby restrained against angular movement.

In testimony whereof I have hereunto affixed my signature.

WILLIAM W. ROBERTSON.
